Attorney

UNITED STATES PATENT OFFICE

CARLOS LYON, OF DECATUR, ILLINOIS

FURNITURE

Application filed February 18, 1929. Serial No. 340,838.

This invention relates to tables, and with regard to certain more specific features, to folding tables.

Among the objects of the invention may be noted the provision of a table of the class described which is readily and easily foldable to occupy a minimum of space, a table of the class described which when in folded position comprises a flat assembly which may be easily stacked with and upon other similar tables, a table which is readily and easily demounted from its standing position to its flat or stacking position, and the provision of a table of the class described which is simple in construction and economical to manufacture. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

25 In the accompanying drawings in which is illustrated one of various possible embodiments of the invention,

Fig. 1 is a side elevation of the table in standing position, certain parts being broken away;

Fig. 2 is a bottom plan view of the table in folded position;

Fig. 3 is a cross section, taken on line 3—3 of Fig. 2;

35 Fig. 4 is an enlarged side elevation of a preferred form of a support or catch, showing a pin therefor;

Fig. 5 is a plan view of said catch shown in Fig. 4;

40 Fig. 6 is a side elevation of an alternate form of support or catch and pin therefor; and

Fig. 7 is a plan view of said alternate form of support or catch and pin shown in Fig. 6.

45 Similar reference characters indicate corresponding parts throughout the several views of the drawings.

Referring now more particularly to Fig. 1, it will be seen that the table comprises a

5 affixed to a side frame or downwardly extending ledge 3. The side frame 3 is preferably made of thicker material than the top 1 for strengthening purposes. Affixed to the under side of the top are two, suitably braced cross-pieces 5 which serve to hold table legs or supports 7 by means of hinges 9. The table legs 7 are more particularly illustrated in Fig. 2. Small bracing blocks 11 are fixed in corners at various places around the table 60 top for strengthening purposes.

Positioned substantially in the center of the under side of the table top 1 is a relatively thin, spacer piece 13. Mounted substantially centrally on said cross-piece 13 is a catch 15, 65 which will be described more in detail hereinafter.

Hinged to each table leg 7 is a brace 17 which passes diagonally upwardly to the cross-piece 13 and through the catch 15, and which serves to hold the table as a whole in a steady upright position. The two braces 17 are not positioned centrally of the top 1 but are located somewhat to each side thereof, as is shown in Fig. 2, so that in folded position they will be contiguous.

In Figs. 1 to 5 is shown the preferred form of the U-shaped piece or catch 15 comprising a base portion 25 adapted to be screwed to said cross-piece 13. Upon the 70 base 25 are spaced pairs of legs 27 adapted to receive between the respective pairs the braces 17 therebetween. Each leg 27 is provided with a hole 29 adapted to slidably receive a pin 31 having a bent handle 33. Two of the legs 27 comprising one pair, are provided with sideward openings 35 adapted to accommodate the passage of a lug 37 so that when the pin is in holding position, the lug 37 is between the two innermost legs 27, 75 the handle 33 functioning as a stop. Thereupon the handle 33 may be rotated so that the lug 37 is out of alignment with the openings 35 (see Fig. 3). Thus the pin 31 is prevented from sliding out. The handle 33 is 80 preferably given a bend in the direction of the lug 37 so that the position of said lug may be determined by noting the position of the handle 33. The handle may be put in a locked position (the lug 37 between the inner- 85

most of legs 27) when the table is in either folded or in unfolded position.

Or the upper ends of the braces 17 may be supported by means of the alternate form of catch 15 (see Figs. 6 and 7), which comprises a right angular U-shaped supporting piece of metal having aligned holes 19 in the sides thereof, and a nail or other preferably pointed and headed pin 21 passing therethrough. The holes 29 are also provided in each of the braces 17, positioned as to hold the legs 7 in substantially right angular or open position, when the pin is passed through aligned holes 19, 29. In the standing position of the table, the pin 21 passes through the sides of the U-piece 15 by way of holes 19 through the holes 29 in each of the braces 17. It is thus seen that a steady structure is attained which supports the table firmly in an upright position. It will be noted that the upper ends of the braces 17 are chamfered to fit snugly against the table top 1. This provides added rigidity.

If it is desired to fold the table, the pin 21 or 31 is removed and the legs fold inwardly to the position shown in Figs. 2 and 3, the braces 17 fall under the legs 7 and rest side by side in a position passing through the U-piece 15. The holes 19 in said U-piece now lie above the top surfaces of the braces 17, so that the pin 21 may be reinserted in the U-piece 15 without passing through the holes in the braces 17 (see Fig. 3) and serving to hold said braces 17 and legs 7 from falling outwardly. The pin 21 or 31 thus serves as a lock, both to hold the legs in standing and in folded position. Inasmuch as the pin 21 needs not be guided through the holes 29 in the braces for holding the braces and legs in folded position the process of folding the table is much simplified. It is to be understood that the lug 37 on the pin 31 is adapted to pass through the openings in the braces by making said openings large enough or moving a slot for accommodating the lug when the braces are in bracing position.

It will be seen by reference to Fig. 3 that the folded legs 7 and braces 17 do not extend beyond the sides 3 of the table top 1. With this feature in view, it is readily seen that the folded tables may readily be stacked with other like folded tables to occupy a minimum of space. It will be seen that the folded table comprises substantially only three layers, the top 1, the braces 17, and the legs 7. The cross pieces 5 in folded position are in the same plane as the braces 17. The three layer construction makes it simple to reassemble the table to standing position and to stack the folded table.

To return the table to standing position from its folded position, it is necessary only to remove the pin 21, open the legs 7 to their proper position, place the braces 17 so that the holes 29 therein are in substantial juxtaposition

with the holes 19 in the U-piece 15, and reinsert the pin 21 through the holes 19 and 29.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In a catch for tables having foldable legs and braces of the class described, a catch comprising spaced pairs of legs, adapted to receive said braces between the respective pairs, holes in said legs and said braces, a pin adapted to pass through said holes to hold the braces unfolded, a lug on the pin, openings associated with at least some of said holes adapted to accommodate said lug in one angular position of the pin, said lug being positioned between the innermost legs of the pairs when in holding position so that the pin may be turned to an angular position whereby the lug prevents withdrawal.

2. In a catch for tables having foldable legs and braces of the class described, a catch comprising spaced pairs of legs, adapted to receive said braces between the respective pairs, holes in said legs and said braces unfolded, a lug on the pin, openings associated with at least some of said holes adapted to accommodate said lug in one angular position of the pin, said lug being positioned between the innermost legs of the pairs when in holding position so that the pin may be turned to an angular position whereby the lug prevents withdrawal and a portion on the pin bent in the direction of the lug for providing a handle and indicating the position of the lug.

In testimony whereof, I have signed my name to this specification this 14th day of February, 1929.

CARLOS LYON.
